EAR PLUG OR THE LIKE

Frederick C. Visor, Englewood Cliffs, N.J., assignor to
Flents Products Co., Inc., New York, N.Y.

Original design application May 29, 1973, Ser. No.
364,855, now Patent No. 234,321. Divided and this
application July 3, 1974, Ser. No. 485,649

Term of patent 14 years

Int. Cl. D24—04
U.S. Cl. D83—1 J

FIG. 1

FIG. 2

FIG. 3

FIG. 1 is a top plan view of an ear plug or the like showing my new design;

FIG. 2 is a side elevation thereof; and

FIG. 3 is a bottom plan view thereof.

This application is a division of design application Ser. No. D. 364,855, filed May 29, 1973 and now Pat. No. D. 234,321.

I claim:

The ornamental design for an ear plug or the like, as shown.
